ASH CONTAINER

Filed March 12, 1948

UNITED STATES PATENT OFFICE

2,637,285

ASH CONTAINER

Delmond L. Getz, Springfield, Ohio, assignor to
The Steel Products Engineering Company,
Springfield, Ohio, a corporation of Ohio

Application March 12, 1948, Serial No. 14,429

7 Claims. (Cl. 110—165)

1

This invention relates to portable ash containers for use in an ash removal system of a domestic heating furnace to receive the ashes from an ash conveyor of the worm feed type.

One of the principal objects of the invention is to provide such an ash container having an ash receiving opening therein for receiving from below the ashes discharged upwardly by the conveyor which is of simple and lightweight construction for economical manufacture and ready handling in use and wherein the ash receiving opening is arranged for such cooperative action with an upwardly projecting discharge tube from the conveyor as to eliminate the necessity of a valve or other closure for the ash receiving opening during removal and dumping of the container.

Another object is to provide such an ash container having therein an ash receiving tube extending upwardly from the ash receiving opening in the bottom of the container and adapted for mounting in telescoping relation upon the upwardly projecting discharge tube from the conveyor to receive ashes therefrom and to discharge the ashes into the container at a position near the top thereof thus eliminating the necessity of a valve or other movable closure for the bottom of the container.

It is also an object of the invention to provide such an ash container wherein the upper ends of the discharge tube of the conveyor and the ash receiving tube in the container cooperate to form a sealed connection supporting the container from the top of the discharge tube in position to receive ashes from the conveyor.

Other objects and advantages of the invention will be apparent from the following description, the accompanying drawing and the appended claims.

In the drawing—

Fig. 1 is a view partly in elevation and partly broken away and in vertical section on the line 1—1 of Fig. 2 showing an ash container in accordance with the invention mounted on an ash conveyor in position to receive ashes therefrom;

Fig. 2 is a view of the container approximately on the line 2—2 of Fig. 1 with parts broken away to illustrate internal construction;

Fig. 3 is a view partly in side elevation and partly in vertical section on the line 3—3 of Fig. 2 showing the relative positions of the container and conveyor while the container is being removed from or mounted on the conveyor; and

Fig. 4 is a fragmentary view on a larger scale taken on the same section line as Fig. 1.

The drawing illustrates a preferred embodiment

2

ment of the present invention in connection with an ash remover stoker of the general type shown in Burton Patent 2,069,940, assigned to the same assignee as this application. As shown, a conveyor tube 18 is provided for conveying the solid fuel to the combustion zone where it is burned in a suitable retort, not shown, and the conveyor 11 removes the ashes from the combustion zone. The conveyor 11 is provided with a discharge opening 12 in the upper part thereof, and a short discharge or outlet tube 13 is secured to the conveyor to transmit ashes upwardly from the discharge opening 12. As shown in Fig. 3, the ash conveyor worm 15 is provided with a reversed flight portion 16, the two flights 15 and 16 terminating below the discharge opening 12 and cooperating to cause the ashes to be lifted upwardly through this opening and through the tube 13.

A funnel 20 of sheet metal in the form of a hollow truncated cone is mounted on the conveyor 11 with its lower end in position to receive ashes from the outlet tube 13. As shown in Fig. 4, the lower end of the funnel 20 fits over the upper end of the discharge tube 13 and is secured as by means of a flanged collar 21 to a generally rectangular flange 22 welded to the outlet tube. This funnel acts in use to receive ashes from the discharge opening 12 and outlet tube 13 of the ash conveyor 11, and its smooth, expanding inner surface guides these ashes upwardly substantially without tumbling or churning until they overflow the top of the funnel and fall into the interior of the container, reference being made in this connection to co-pending application of Joseph E. McAdams, Serial No. 723,811, filed January 23, 1947, now Patent No. 2,509,872, issued May 30, 1950, and assigned to the same assignee as this application. A ring or collar 25 is welded or otherwise secured around the upper end of the funnel 20, and the upper portion 26 of this ring is flared outwardly at a substantially greater angle than the angle of taper of the remainder of the funnel, for example an angle of 45° to the vertical as opposed to an angle of taper of approximately 6° for the remainder of the funnel.

The container 30 is adapted for removable mounting on the ash conveyor 11 to receive the ashes from funnel 20, this container being portable to facilitate ready carrying away and dumping of the ashes. It is generally rectangular in horizontal section, and it is provided with a suitable top 31 sealed against a gasket 32 to prevent escape of ashes or dust therefrom. The top 31 is provided with a handle 33, and two handles 34 are fastened to the ends for use in

handling the container. The bottom 35 of the container 30 is provided with an ash receiving opening 36 symmetrically located at the center thereof and of sufficient diameter to receive the flared ring or collar portion 25 of funnel 20 therethrough.

A tube 40 open at both ends thereof and of substantially the same inner diameter as the ash receiving opening 36 has its lower end secured to the bottom 35 of the container in concentric relation with the opening 36. As shown in Fig. 4, the lower end of tube 40 is flanged at 41 to facilitate welding or bolting to the bottom of the container, and the tube extends upwardly within the container to a position spaced well above the container bottom 35. A ring or collar 42 is welded or otherwise secured around the upper end of the tube 40, and this ring includes an annular flange extending inwardly of tube 40.

The ring 42 cooperates with ring 25 to support the tube 40 and the container on funnel 20. Referring to Fig. 4, the upper part of the ring 42 includes an outer portion 44 which is tapered upwardly and an inner portion 45 which is tapered downwardly and extends radially inwardly with respect to the tube to a sufficient distance to overlap the upper end of the ring 25. This inner portion 45 of ring 42 is tapered at substantially the same angle as the portion 26 of the ring 25, so that the adjacent surfaces of these tapered or flared ring portions engage in sealing relation when the tube and funnel are in substantially fully telescoped relation, and thus cooperate to support the container and the tube 40 on the top of funnel 20. The outer ends of the flange 22 are turned upwardly at 46 to aid in positioning the container on the funnel.

It will be seen that with this construction of the container 30 and funnel 20, the ashes fed upwardly from the conveyor 11 into the funnel will spill over the top of the tube 40 and ring 42 and fall down into the interior of the container, the discharge of ashes from the funnel into the container thus taking place near the top of the container. When the ashes have accumulated to a sufficient extent to make dumping of the container advisable, it can be simply lifted up by means of the handles 34 and carried away for dumping. Since the upper or discharge end of the tube 40 is near the top of the container, there will be no danger of accumulated ashes spilling out while the container is being moved, and accordingly it is unnecessary to provide a valve or other closure for the discharge opening 36. The rectangular configuration of the container is helpful if the ashes have accumulated above the top of the funnel, since such excess accumulation can be readily pushed or brushed out into the space at either end of the container before it is lifted. This container can thus be made of relatively light sheet stock, and it is therefore economical to produce and easy to handle in use.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. Ash receiving apparatus of the character described for use with a furnace having a retort defining a combustion zone, comprising an ash conveyor leading from said retort and having a discharge opening in the upper part thereof at

a position outside of and spaced laterally from said furnace, a discharge tube secured to said conveyor at said discharge opening and projecting upwardly therefrom to guide ashes upwardly from said opening, a removable container separate from said discharge tube and having an ash receiving opening in the bottom thereof, a tube open at both ends thereof secured to the bottom of said container in concentric relation with said ash receiving opening and extending upwardly therefrom within said container to a position spaced above said container bottom, said container tube being of sufficient size to receive said discharge tube in telescoping relation therewith and being of substantially smaller diameter than said container to leave an annular space surrounding said container tube within said container, and means for removably supporting said container on said conveyor with said tubes in substantially fully telescoped relation to effect discharge of ashes from said discharge tube into said annular space within said container over the upper end of said container tube.

2. Ash receiving apparatus of the character described for use with a furnace having a retort defining a combustion zone, comprising an ash conveyor leading from said retort and having a discharge opening in the upper part thereof at a position outside of and spaced laterally from said furnace, a discharge tube secured to said conveyor at said discharge opening and projecting upwardly therefrom to guide ashes upwardly from said opening, a removable container separate from said discharge tube and having an ash receiving opening in the bottom thereof, a tube open at both ends thereof secured to the bottom of said container in concentric relation with said ash receiving opening and extending upwardly therefrom within said container to a position spaced above said container bottom, said container tube being of sufficient diameter to receive said discharge tube in telescoping relation therewith and being of substantially smaller diameter than said container to leave an annular space surrounding said container tube within said container, and means for removably supporting said container on said conveyor with said tubes in substantially fully telescoped relation to effect discharge of ashes from said discharge tube into said annular space within said container over the upper end of said container tube.

3. Ash receiving apparatus of the character described for use with an ash conveyor for removing ashes from the combustion zone of a furnace and having a discharge opening in the upper part thereof at a position spaced from the combustion zone, comprising a discharge tube secured to said conveyor at said discharge opening and projecting upwardly therefrom to guide ashes upwardly from said opening, a removable container having an ash receiving opening in the bottom thereof, a tube open at both ends thereof secured to the bottom of said container in concentric relation with said ash receiving opening and extending upwardly therefrom within said container to a position spaced above said container bottom, said container tube being of sufficient diameter to receive said discharge tube in telescoping relation therewith, and an inturned flange at the upper end of said container tube adapted to overlap the upper end of said discharge tube for removably supporting said container tube and container on said discharge tube with the upper end of said discharge tube in position to discharge ashes over

the upper end of said container tube and into the interior of said container.

4. Ash receiving apparatus of the character described for use with an ash conveyor for removing ashes from the combustion zone of a furnace and having a discharge opening in the upper part thereof at a position spaced from the combustion zone, comprising a discharge tube secured to said conveyor at said discharge opening and projecting upwardly therefrom to guide ashes upwardly from said opening, a removable container having an ash receiving opening in the bottom thereof, a tube open at both ends thereof secured to the bottom of said container in concentric relation with said ash receiving opening and extending upwardly therefrom within said container to a position spaced above said container bottom, said container tube being adapted to receive said discharge tube in telescoping relation therewith, said discharge tube having an outwardly flared portion at the upper end thereof, and an inturned and downwardly extending flange at the upper end of said container tube adapted to overlap and engage within said flared end of said discharge tube and in sealing relation therewith for removably supporting said container tube and container on said discharge tube with the upper end of said discharge tube in position to discharge ashes over the upper end of said container tube and into the interior of said container.

5. Ash receiving apparatus of the character described for use with a furnace having a retort defining a combustion zone, comprising an ash conveyor leading from said retort and having a discharge opening in the upper part thereof at a position outside of and spaced laterally from said furnace, a hollow cone forming a funnel secured at its smaller end to said conveyor at said discharge opening and projecting upwardly therefrom to guide ashes upwardly from said opening, a removable container separate from said funnel and having an ash receiving opening in the bottom thereof, a tube open at both ends thereof secured to said container bottom in concentric relation with said ash receiving opening and extending upwardly therefrom within said container to a position spaced above said container bottom, said tube being of substantially smaller diameter than said container to leave an annular space surrounding said tube within said container, said ash receiving opening and said tube being of sufficient diameter to receive said funnel in telescoping relation with said tube, and means for removably supporting said container on said conveyor with said tube and said funnel in substantially fully telescoped relation to effect discharge of ashes from said funnel into said annular space within said container over the upper end of said tube.

6. Ash receiving apparatus of the character described comprising an ash conveyor for removing ashes from the combustion zone of a furnace and having a discharge opening in the upper part thereof at a position spaced from the combustion zone, a hollow cone forming a funnel se- 65

cured at its smaller end to said conveyor at said discharge opening and projecting upwardly therefrom to guide ashes upwardly from said opening, a removable container having an ash receiving opening in the bottom thereof, a tube open at both ends thereof secured to said container bottom in concentric relation with said ash receiving opening and extending upwardly therefrom within said container to a position spaced above said container bottom, said ash receiving opening and said tube being of sufficient diameter to receive said funnel in telescoping relation with said tube, and cooperating means at the upper ends of said tube and funnel for removably supporting said tube and container on said funnel in position to receive ashes discharged from said funnel over the upper end of said tube and into the interior of said container.

7. Ash receiving apparatus of the character described for use with an ash conveyor for removing ashes from the combustion zone of a furnace and having a discharge opening in the upper part thereof at a position spaced from the combustion zone, comprising a hollow cone forming a funnel secured at its smaller end to said conveyor at said discharge opening and projecting upwardly therefrom to guide ashes upwardly from said opening, the upper end of said funnel including a portion flared outwardly at an angle greater than the angle of taper of the remainder of said funnel, a removable container having an ash receiving opening in the bottom thereof, a tube open at both ends thereof secured to said container bottom in concentric relation with said ash receiving opening and extending upwardly therefrom within said container to a position spaced above said container bottom, said ash receiving opening and said tube being of sufficient diameter to receive said funnel in telescoping relation with said tube, and means forming at the upper end of said tube an annular flange extending inwardly of said tube, said flange including an inner portion tapered downwardly of said tube at substantially the same angle as said flared portion of said funnel, said tapered portion of said flange being of lesser inner diameter than the outer diameter of said flared portion of said funnel to seat in sealing relation within said flared funnel portion and to form a removable support for said tube and container on said funnel in position to receive ashes discharged from said funnel over the upper end of said flange and into the interior of said container.
